TYPEWRITER COVER AND THE LIKE

Théodore Grange, Paris, France, assignor to Constructors Limited, Erdington, Birmingham, England, a company of Great Britain

Application January 24, 1933, Serial No. 653,262
In France January 29, 1932

3 Claims. (Cl. 45—68.1)

This invention has for object a new cover casing for typewriter machines of all sizes and makes when out of service or when being transported and for use in lieu of the separate rigid covers and linen and like covers usually employed hitherto.

Rigid covers are cumbersome and take up, in an office, useful space unless used for an improvised purpose such as for the reception of correspondence, with the result that the typewriter frequently is no longer covered up at night and remains exposed to dust. As regards fabric covers or those made of imitation leather fabric they are very inconvenient to fit in place, unsightly, 10 become readily torn and in no way protect the machine against shock or knocks.

The invention consists essentially in a series of sectors or hoops pivotal about a transverse axis and fitting the one within the other behind 20 and above the carriage of the machine, a simple pull on a knob provided for the purpose or the rotation of a milled head at the side being sufficient to cause the fan-like spreading out of the device so as to completely cover over the machine, 25 said cover being locked at the front of the keyboard.

The accompanying drawing shows, a typewriter cover constructed according to the present invention and wherein:

30 Figure 1 is a front elevation of the cover in its closed position; the covered typewriter being shown in dotted lines;

Figure 2 is a sectional side elevation of the cover partly raised, the section being taken on the line II—II of Figure 1;

Figure 3 is a plan of the cover open and with a modification applied thereto;

Figure 4 is a section to a larger scale of one of the hubs, the section being taken on the line 40 IV—IV of Figure 2, but only the hub portions of the various parts being shown;

Figure 5 is a side elevation to a larger scale of the hub portions of three consecutive sectors.

The new protecting cover consists essentially of 45 a series of cut out sections or crescents and suitably shaped or curved to form flat rectangular or rounded hoops 3 all turning about two common pivots 2 in order to come, or fit one within the other on the frame 1 of said machine or around 50 it as shown, or they may be spread out fan-wise over the keyboard so as to cover and enclose the parts of the machine fully sheltering it from dust, giving at the same time the appearance of a half drum or a half sphere according to the 55 shape given to the sections. The pivots 2 can be

fitted anywhere conveniently on existing machines or in new machines cast during the manufacture thereof or may be mounted on a separate frame or casing 1^a, as shown, in which the machine is mounted. Milled knobs 4 are provided permitting of easy manipulation of the cover in both directions while the last section is fitted with a lock 5 with safety catch automatically engaging at the front of the base of the frame or casing 1^a to hold the device closed and to maintain the tension of the cover material, the lock 5 carrying a button or knob which can be used for opening the lock and for lifting the folding cover.

In typewriter machines the base or frame would be dimensioned so as to contain and hide away 15 at 6 the closed section in such a manner that the cover will take up no room. Finally said base might have lateral or front handles 7 to facilitate transport replacing those ordinarily fitted to rigid covers.

The sections forming the cover are made of any appropriate material which is sufficiently rigid, resistant, and thin such as sheet metal, aluminium, plastic materials, thin ply wood, fibre or may be of composite material or reinforced and 25 so on. They may consist of half-hoops over which is stretched a cover of leather or imitation leather. The last of the sections coming in contact with the front part of the base forward of the keys has a flange 12 ensuring tightness and 30 covering the other sections when the cover is open.

The successive carrying along of the sliding elements 3 one by the other at the unfolding or folding up of the cover is effected by means of pins 35 14 provided on hubs 13 engaging in curved slots 13^a cut out in the hub 13 of the next element; the tightness between the sections 3 is ensured by a small band of felt or velvet 15 glued as shown in Figs. 1 and 2 which also gives silent and gentle 40 action, preventing one element from scratching the next. Such a circular hub 13 is provided on each side of the machine. The arrangement of the pins on each hub and the length of the slots 13^a are such that at the unfolding for covering 45 over the machine, the finger 14 of the first element commences to travel through the slot 13^a of the second element; then abutting at the end of its stroke against the end of the slot 13^a, it carries along the second element. The finger 50 carried on each of its two hubs by the second element acts similarly in regard to the third element and so on in sequence.

In the opposite direction the operation is identical, the first element commencing by closing 55

inside the second and at that moment the two lateral fingers having travelled through their slots push back the second element which in its turn enters the third element and so on. Three hubs of consecutive elements are shown in Fig. 5.

Finally, in the case where the cover is not manipulated at its centre and where the elements are fairly long such as in large models for accounting machines, warping or jamming is prevented by fitting to the casing a driving arrangement arranged at both sides of the cover which causes the two lateral axes to turn evenly and simultaneously through the same angle. This arrangement consists essentially in a transverse axis 16 connecting through pinion wheels 17, 18 to the two pivots 2. The pinion wheels 17 are fast with the hubs of the first or front sections. To avoid clumsiness the axis 16 is, in most types of machine, located at the rear of the machine as shown in Fig. 5, and carries the pinion wheels 18 connected by chains 19 on each side and driven by the wheels 17.

I claim:

1. A cover for typewriters and the like comprising a series of telescoping sections pivotally mounted upon a base, circular hubs on said sections, means carried by said hubs for moving the sections in succession and limiting the movements thereof.

prising a series of telescoping sections pivotally mounted upon a base, circular hubs on said sections, means carried by said hubs for moving the sections in succession and limiting the movements thereof.

2. A cover for typewriters and the like comprising a series of telescoping sections pivotally mounted on a base, hubs on said sections, slots in said hubs, a lateral projection carried by one of said hubs, said projection operably engaging the slots of said hubs for moving the sections in succession.

3. A cover for typewriters and the like comprising a series of telescoping sections pivotally mounted on a base, means for packing the edges of said sections, hubs on said sections, arcuate slots in said hubs, a lateral projection carried by one of said hubs, said projection operably engaging the slots of the remaining hubs for moving the sections in succession, a toothed pinion carried by the end sections, an endless chain connecting said pinions, and means for turning the pinion of the end section for operating the cover.

THÉODOSE GRANGE.
